UNITED STATES PATENT OFFICE

WILLIAM A. CHRYST AND GEORGE W. ELSEY, OF DAYTON, OHIO, ASSIGNEES, BY MESNE ASSIGNMENTS, TO DELCO-REMY CORPORATION, OF DAYTON, OHIO, A CORPORATION OF DELAWARE

ENGINE STARTING APPARATUS

Application filed October 30, 1926. Serial No. 145,318.

This invention relates to apparatus for starting an internal-combustion engine, and more particularly to that type of apparatus which includes an electric motor operating a shaft which is normally disconnected from the engine, but may be connected therewith by means including a pinion movable along the shaft into engagement with the gear and engine to be started and to rotate with the shaft, said connecting means including provisions whereby the pinion will be automatically demeshed from the engine gear when the engine becomes self-operative.

One object of the present invention is to minimize wear and breakage of the gear teeth by providing manually operable means of simple and economical construction for moving the pinion axially into engagement with the engine gear and for rotating the pinion in case of gear tooth abutment in order that the pinion may be nearly fully meshed with the engine gear before the motor is operated.

Further objects and advantages of the present invention will be apparent from the following description, reference being had to the accompanying drawings wherein a preferred embodiment of one form of the present invention is clearly shown.

In the drawings:

Fig. 1 is a fragmentary view partly in longitudinal section showing a form of engine starting apparatus embodying the present invention, the apparatus being shown in normal position in which the motor pinion is disconnected from the engine gear;

Fig. 2 is a sectional view on the line 2—2 of Fig. 1;

Fig. 3 is a plan view of a sheet metal punching used to form one of the elements of the apparatus shown in Fig. 1;

Fig. 4 is a view similar to Fig. 1 showing the apparatus in condition for starting the engine;

Fig. 5 is a view similar to Fig. 1 showing the apparatus after the engine has become self-operative, but before the manually operable member which controls the starter has been returned to normal position; and

Fig. 6 is a fragmentary sectional view of

the pinion retaining means, on a larger scale than the other views.

Referring to the drawings, 20 designates the field frame of an electric motor which is attached by any suitable means not shown to a housing 21. The field frame 20 and the housing 21 support a shaft 22 which is operated by the electric motor, said shaft 22 usually being an extension of the motor armature shaft. The shaft 22 is provided with spiral splines 23 and that portion of the splines 23 which is located between the lines 23a and 23b in Fig. 1 is slightly smaller in diameter than the diameter of the remaining spirally splined portion. The shaft 22 is provided with an annular groove 24, which receives the wire split ring 25. The shaft 22 cooperates with thrust washer 26 bearing against a machined surface 27 provided by the housing 21.

A pinion 30, which is provided internally with spiral splines, is mounted to slide longitudinally along the shaft 22 into engagement with the flywheel gear 31 of an engine to be started. Normally the pinion 30 is out of mesh with engine gear 31 and is supported by that portion of the splines 23 which is of smaller diameter, namely that portion located between the lines 23a and 23b. The splined portion of smaller diameter is connected with the splined portion of larger diameter by shoulder portions 32, which serve as obstructions tending to prevent drifting of the pinion into engagement with engine gear while the engine is running. When the pinion is in full mesh with the engine gear, the wire split ring 25 will be received by an annular groove 33 provided on the interior of the pinion hub. As the pinion 30 is moved toward the right of the drawings into engagement with the ring 25, said ring is first engaged by an annular abutment 34 of smaller internal diameter than the normal external diameter of the ring 25. As the pinion is forced against the ring, the ring will be contracted slightly in order that the obstruction 34 may pass over it. Then the ring will expand into the grooves 33. When the engine becomes self-operative and the pinion is automatically demeshed from the

engine gear, the ring 25 will contract again to permit the obstruction 34 to pass beyond it. In this way the pinion is yieldingly maintained in substantially full mesh with the engine gear so that, during the engine cranking operation, axial movement of the pinion due to variation in the torque required to crank the engine will be practically eliminated. It is therefore apparent that the ring 25 serves as a stop, limiting the movement of the pinion 30 toward the right of the drawings and also as a member for yieldingly maintaining the pinion in full mesh with the engine gear.

15 The housing 21 supports a bolt or stub shaft 40 which provides a journal for the hub 41 of a manually operable lever 42. The arm 42a of the lever 42 is so located as to engage the plunger 43 of a starting motor switch 44, the casing 45 of which is secured to the field frame 20 by screws 46. The lever arm 42a is connected with a pedal 47, which extends through a cup-shaped member 48 carried by the floor board 49 of the automobile. A 20 spring 50, which is located between the member 48 and the head of the rod 47, tends to maintain the lever 42 in the position shown in Fig. 1.

In order that the pinion 30 may be moved 30 into mesh with the engine gear 31 before the motor switch is closed, means are provided for transmitting motion from the lever 42 to the pinion 30 so that the pinion will be moved endwise into mesh with gear 31 and 35 will be rotated in case the teeth of the pinion collide with the end faces of the teeth of the gear 31, said means being so constructed and arranged that the motor switch cannot be closed until the pinion has been substantially 40 meshed with the engine gear and that there will be no interference with demeshing of the pinion from the engine gear after the engine starts, although the lever 42 may still be maintained in operating position. The motion 45 transmitting means comprise chiefly two members which are connected for movement together longitudinally of the shaft so that one of the members may engage the pinion 30 to move it into mesh with the gear 31, the 50 connection between said members being such that in case motion of the pinion is arrested by the engine gear, one of the members will impart rotary motion to the other member which engages the pinion. The pinion engaging member and pinion provide axially engaging clutching devices so that the rotary motion produced by motion transmitting means will be imparted to the pinion. One 55 of the motion transmitting members is a pin or stud 51 which is attached to the arm 42a of the lever 42, and the other member is a sleeve 52 which is provided with a slot 53 located obliquely to the axis of the shaft 42 and adapted to receive the pin 51.

60 The sleeve 52 is provided with teeth 54

which function as a driving clutch member for axially engaging a driven clutch member provided by beveling, as shown at 55 in Fig. 4, the ends of the teeth of the pinion 30 in order to provide clutch teeth 56. In the 70 particular form of the invention shown in the drawings the pinion is a nine tooth pinion and hence is provided with nine clutch teeth 56. The sleeve 52 may be provided with nine teeth 54, but, if it is desirable to reduce 75 the maximum of lost rotary motion between the clutch members, the sleeve may have a multiple of the number of teeth 56, for example eighteen teeth, as shown.

80 The sleeve 52 is formed preferably from a blank or punching of flat sheet material as shown in Fig. 3. The blank is provided initially with the teeth 54 and the slot 53 and with a dovetail tang 57 adapted to be received by dovetail notch 58. The blank shown in Fig. 3 is formed into a cylinder, the tang 57 being received by the notch 58 in order to prevent opening the joint of the cylinder. The sleeve 52 is supported by a hub 60, having spaced flanges 61 and 62 so as to define 90 an annular space 63 which may receive one end of the pin 51. The flange 62 is provided with an annular groove 64 and the wall of the sleeve 52 is forced into the groove 64 as indicated by the annular groove 65 in the sleeve. This construction tends to stiffen the sleeve, 95 to prevent it unfolding from cylindrical form and to prevent relative longitudinal movement between the hub and the sleeve.

The method of using the invention is as 100 follows:

Normally the starting apparatus is in the position shown in Fig. 1 in which the pinion 30 is demeshed from the engine gear and the motor switch is open. To start the engine the pedal 47 is depressed thereby causing the lever 42 to rotate counter-clockwise in order to move the pin 51 and the sleeve 52 longitudinally of the shaft and to the right of the drawings. The slot 53 is a spiral 105 of variable pitch and the pin 51 engages that portion of the slot wall which is the lesser in pitch so that, initially, the tendency of the pin to move the sleeve 52 longitudinally is greater than the tendency to rotate the sleeve; therefore the sleeve 52 will move toward the right and the clutch teeth 54 will engage the clutch teeth 56 provided by the pinion 30. In case the pinion teeth abut the ends of the gear teeth, motion of the sleeve 52 will be arrested; but, if the operator continues to press the pedal 47, the pinion 30 will be rotated due to the cooperation of the pin 51 with the spiral slot 53 of the sleeve. When the pinion teeth register with the gear tooth space of the gear 31, the pinion 30 will move into mesh with the gear 31. After the pinion 30 has been nearly fully meshed with the gear 31, the lever arm 42a will engage the switch 110 plunger 43 and the motor switch 44 will be 115 120 125 130 135

closed. When this occurs, the shaft 22 will be rotated in a clockwise direction as viewed from the right of the drawings and as indicated by the arrows 70 in Figs. 1 and 4, thereby causing the pinion 30 to be moved away from the sleeve 52 and into engagement with the ring 25, then the pinion 30 will rotate with the shaft 22 and the engine gear 31 will be rotated to crank the engine.

When the engine becomes self-operative the pinion will be automatically demeshed. Demeshing will occur although the operator may maintain pressure upon the pedal 47, as it is apparent from Figs. 4 and 5 that the sleeve 52 is free to move toward the left in order not to interfere with the demeshing of the pinion. While the pin and slot connections between the sleeve and the lever permit movement of the sleeve by the pinion when the pinion is demeshed from the engine gear, this operation does not always occur. It happens more frequently that the sleeve 52 is returned to normal position before the engine becomes self-operative. This feature of the invention is due to the fact that there is always some friction between the sleeve hub 60 and the shaft 22; therefore when the shaft 22 is operated by the motor, the hub 60 and the sleeve 52 will be rotated in the direction of the arrow 70 while the pin 51 is maintained in the position shown in Fig. 4. Consequently the rotation of the shaft 22 before the engine becomes self-operative will cause the sleeve 52 to be threaded along the pin 51 and to be moved into the normal or non-operating position shown in Fig. 5. Therefore demeshing of the pinion 30 will take place without any engagement between the clutch teeth 54 and 56.

After the operator releases the pedal 47, the spring 50 will be released to move the pedal upwardly and to return the lever 42 to the position shown in Fig. 1. During this operation a spring 43a will be released to move the switch plunger 43 from the position shown in Fig. 4 to that shown in Fig. 1 in order to open the motor switch.

Means cooperating with the sleeve 52 and the shaft 22 are provided for resisting the tendency of the sleeve to rotate at the beginning of its movement from non-operating position, or toward the right from the position shown in Fig. 1. This means comprises a metal brake disc 80 fixed to the shaft 22 a floating disc 81 of yieldable material, such as cork, and a brake disc 82 attached to the sleeve hub 60. Disc 82 is provided with a hole for receiving a tang 83 provided by the sleeve 52, in order drivingly to connect said disc and sleeve. The parts 80, 81 and 82 are maintained normally in engagement by the spring 50 which urges the lever arm 42b toward the left as viewed in Fig. 1. Hence, normally, the brake members 80, 81 and 82 tend to maintain the sleeve 52 fixed relative to the shaft 22.

When the lever arm 42b begins its movement toward the right, the brake members are apparently not instantly disengaged, but tend to resist rotation of the sleeve 52 after the sleeve has begun to move toward the right. Apparently the cork disc 81 expands axially sufficiently to maintain friction between the brake members after motion of the sleeve has begun. Since resistance to endwise movement of the sleeve is overcome before removing resistance to rotation of the sleeve, the tendency of the sleeve to move endwise will be greater, initially, than the tendency for the sleeve to rotate. Hence the possibility of the sleeve rotating without moving endwise has been minimized.

The brake members 80, 81 and 82 cooperate with the pinion shifting mechanism for the further purpose of bringing the motor shaft 22 quickly to rest after the operator releases the pedal 47. It is apparent that the spring 50 will urge the brake member 82 toward the brake members 81 and 80. Since the brake member 82 is prevented from rotating freely with the shaft 22 by reason of engagement of the pinion 30 with the sleeve 52, the brake disc 82 will function as a stationary brake member cooperating with the movable brake discs quickly to arrest motion of the shaft 22. In case the engine should make a false start, that is, if the engine should become self-operative for a time sufficient to demesh the pinion 30 from the gear 31 but should not continue to be self-operative, the operator will not need to wait for a substantial period to elapse for the motor shaft to stop rotating before repeating the pinion shifting operation. In case of a false start, the operator may release the pedal to restore the gear shifting mechanism to normal condition, and then may almost immediately depress the pedal to repeat the starting operation.

In order to increase friction between the sleeve 52 and the shaft 22 and to insure the automatic retraction of the sleeve from the pinion when the motor operates the sleeve hub 60 carries a spring pressed plunger 85 bearing against the shaft 22 as shown in Fig. 1.

In case of back-fire during the gear meshing operation, the pinion will be moved toward the right from the position shown in Fig. 4, and out of engagement with the sleeve clutch teeth.

From the foregoing description of the construction and mode of operation of the present invention, it will be apparent that the invention possesses the advantages of simplicity and durability of construction and reliability of operation. The number of parts required for the starter drive is very small and they may be constructed and assembled at very low cost. Owing to the simplicity of construction the parts may be made relatively rugged and substantial and therefore

very durable. With this form of invention the starter pinion is meshed with the engine gear before the motor is operated, hence liability of danger to the gear teeth has been 5 substantially reduced. The pinion may be demeshed from the engine gear automatically, should the operator forget to release the starter pedal when the engine becomes self-operative. Since the starter drive provides 10 no obstruction to the demeshing movement of the pinion the apparatus will be relatively quiet in operation.

While the form of embodiment of the present invention as herein disclosed, constitutes 15 a preferred form, it is to be understood that other forms might be adopted, all coming within the scope of the claims which follow.

What is claimed is as follows:

1. Engine starting apparatus comprising, 20 in combination, a motor; a shaft operated by the motor; means for connecting the shaft with the gear of an engine to be started and including a pinion mounted on the shaft for longitudinal movement thereof and having a 25 hub which is directly driven by the shaft and which remains drivingly connected with the shaft for all positions of the pinion and provisions whereby the pinion will be automatically demeshed from the engine gear when 30 the engine starts; and manually operable means for shifting the pinion endwise into mesh with the engine gear and for rotating the pinion in case the pinion teeth collide with the engine gear teeth, said means including 35 two members movable along the shaft, one of said members being rotatable, and one of said members having a part located oblique to the direction of bodily motion of said members and engaged by the 40 other member whereby the rotatable, manually operable member may be rotated by the other member when moved along the shaft, and means for connecting the rotatable member with the pinion.

2. Engine starting apparatus comprising, 45 in combination, a motor; a shaft operated by the motor; means for connecting the shaft with the gear of an engine to be started and including a pinion mounted on the shaft for longitudinal movement thereof and having a 50 hub which is directly driven by the shaft and which remains drivingly connected with the shaft for all positions of the pinion and provisions whereby the pinion will be automatically demeshed from the engine gear when 55 the engine starts; a device for shifting the pinion endwise into mesh with the engine gear and for rotating the pinion in case the pinion teeth collide with the engine gear teeth, said 60 device including two members movable longitudinally of the shaft, said members having an oblique slot and pin connection with each other for movement together longitudinally of the shaft and for angular movement one relative to the other when longitudinal move-

ment of one of the members is obstructed, said member being adapted to shift the pinion longitudinally and to rotate the pinion, and manually operable means for actuating said device.

3. Engine starting apparatus comprising, 70 in combination, a motor; a shaft operated by the motor; means for connecting the shaft with the gear of an engine to be started and including a pinion mounted on the shaft for longitudinal movement thereof and having a hub which is directly driven by the shaft and which remains drivingly connected with the shaft for all positions of the pinion and provisions whereby the pinion will be automatically demeshed from the engine gear when 75 the engine starts; a device for shifting the pinion endwise into mesh with the engine gear and for rotating the pinion in case the pinion teeth collide with the engine gear teeth, said device including a sleeve movable along the shaft and provided with a slot oblique to the shaft, and a pin movable longitudinally of the shaft and engaging the slot, 80 whereby the pin and sleeve may move together to move the pinion into mesh with the engine gear and whereby the sleeve may be rotated in case movement thereof is obstructed, said sleeve and pin having clutching means for imparting rotation to the pinion, and manually operable means for actuating said device.

4. Engine starting apparatus according to 85 claim 3 in which the sleeve is provided with a toothed clutch portion which engages a toothed clutch portion provided by the pinion, 90

5. Engine starting apparatus according to 95 claim 3 in which the sleeve is provided with a toothed clutch portion which engages clutch teeth provided by the ends of the pinion teeth adjacent the sleeve.

6. Engine starting apparatus according to 100 claim 3 in which the slot in the sleeve is variable in pitch from lesser pitch to greater pitch and the pin normally engages the portion of the slot wall which is lesser in pitch, so that initially the tendency of the pin to move the sleeve endwise is greater than the 105 tendency to rotate the sleeve.

7. Engine starting apparatus according to 110 claim 3 in which the slot in the sleeve is so arranged that rotation of the sleeve by the shaft when driven by the motor in the predetermined direction of rotation for starting the engine will cause the sleeve to be moved away from the pinion.

8. Engine starting apparatus according to 115 claim 3 in which the pinion is connected with the motor shaft by spiral splines thereon, and in which the lead of the slot in the sleeve is the same in direction as the lead of the splines on the shaft.

9. Engine starting apparatus comprising, 120 in combination, a motor; a motor switch; a 125

- shaft having spiral splines driven by the motor; a pinion having its hub directly driven by the splined portion of the shaft and slidably therealong into mesh with an engine gear; a manually operable member for closing the motor switch; and means for transmitting motion from the manually operable member to the pinion to mesh the pinion with the gear, said means preventing closing the motor switch until after the pinion partly meshes with the gear, and said means including a pin element and an element having a slot oblique to the shaft and engaged by the pin, said elements being movable together along the shaft, and one of them engagable with the pinion and having provisions adapted to impart rotation to the pinion in case the pinion teeth collide with the engine gear teeth.
10. Engine starting apparatus according to claim 9 in which the element having the slot oblique to the shaft is a sleeve slidable along the shaft and in which the pin which projects into the slot is supported by the manually operable member, said sleeve and pinion having axially engageable clutch members whereby the sleeve may impart rotation to the pinion in case the pinion teeth collide with the engine gear teeth.
11. Engine starting apparatus comprising in combination, a motor; a motor switch mounted upon the motor field frame; a housing extending from one end of the motor frame; a shaft driven by the motor and supported by the motor frame and housing and provided with a spirally splined portion; a pinion having its hub directly connected with said splined portion of the shaft; a lever pivoted on the housing and adapted to operate the motor switch and having an arm extending within the housing and carrying a pin movable longitudinally of the shaft; a sleeve movable along the shaft and having a spiral slot receiving the pin; and axially engageable clutching means provided by the sleeve and pinion whereby the pinion will be rotated in case the pinion teeth abut the engine gear.
12. Engine starting apparatus comprising, in combination, a motor; a motor switch mounted upon the motor field frame; a housing extending from one end of the motor frame; a shaft driven by the motor and supported by the motor frame and housing and provided with a spirally splined portion; a pinion having its hub directly connected with said splined portion of the shaft, axially engageable driving and driven clutch members, the driven member being provided by the pinion; a device for engaging the clutch members to move the pinion endwise into mesh with the engine gear and for rotating the clutch members in case the pinion teeth abut the engine gear teeth; manually operable means for causing said device to mesh the pinion with the gear and then for causing the switch to be closed; and means responsive to the operation of the motor while cranking the engine for causing the driving clutch member to be retracted from the driven clutch member.
13. Engine starting apparatus, comprising, in combination, a motor; a shaft operated by the motor; means for connecting the shaft with the gear of an engine to be started and including a pinion mounted on the shaft for longitudinal movement thereof and having a hub which is directly driven by the shaft and which remains drivingly connected with the shaft for all positions of the pinion and provisions whereby the pinion will be automatically demeshed from the engine gear when the engine starts; and manually operable means for shifting the pinion endwise into mesh with the engine gear and for rotating the pinion in case the pinion teeth collide with the engine gear teeth, said means including a pin movable longitudinally of the shaft and extending through an oblique slot pre-formed in a sheet metal piece formed into a cylinder and supported by a hub slidable along the shaft.
14. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; means for moving the pinion along the shaft; and means for yieldingly retaining the pinion in a certain position relative to the shaft, said means including a resilient split ring member engageable with an annular abutment member, one of said members being carried by the shaft and the other by the pinion, the part carrying the split ring having a groove into which the ring is forced by engagement with the abutment member.
15. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; means for moving the pinion along the shaft; and means for yieldingly retaining the pinion in a certain position relative to the shaft, said means including a resilient split ring member carried by the shaft within an annular groove and an annular abutment member provided internally of the pinion hub and having its in-

ternal diameter slightly less than the normal outside diameter of the ring.

16. Engine starting apparatus comprising, in combination, a motor; a shaft operated by

5 the motor; means for connecting the shaft with the gear of an engine to be started and including a pinion mounted on the shaft for longitudinal movement thereof and rotary movement therewith and provisions whereby

10 the pinion will be automatically demeshed from the engine gear when the engine starts; a device for shifting the pinion endwise into mesh with the engine gear and for rotating the pinion in case the pinion teeth collide with

15 the engine gear teeth, said device including a sleeve movable along the shaft and provided with a slot oblique to the shaft, and a pin movable longitudinally of the shaft and engaging the slot, whereby the pin and sleeve

20 may move together to move the pinion into mesh with the engine gear and whereby the sleeve may be rotated in case movement thereof is obstructed, said sleeve and pinion having clutching means for imparting rotation to

25 the pinion; manually operable means for actuating said device; and means tending to resist rotation of the sleeve relative to the shaft at the beginning of the movement of the sleeve from its non-operating or normal position.

30 17. Engine starting apparatus according to claim 16 in which a brake is provided between the sleeve and the shaft, said brake including a friction disc of yieldable material, and in

35 which a spring cooperates with the manually operable means to urge the sleeve into non-operating position and into operative engagement with said brake, said friction disc expanding axially at the beginning of the movement of the sleeve from non-operating position

40 for the purpose specified.

18. Engine starting apparatus comprising, in combination, a motor; a shaft operated by the motor; means for connecting the shaft with the gear of an engine to be started and

45 including a pinion mounted on the shaft for longitudinal movement thereof and rotary movement therewith and provisions whereby the pinion will be automatically demeshed from the engine gear when the engine starts; a device for shifting the pinion endwise into mesh with the engine gear and for rotating the pinion in case the pinion teeth collide with the engine gear teeth, said device including

50 a sleeve movable along the shaft and provided with a slot oblique to the shaft, and a pin movable longitudinally of the shaft and engaging the slot, whereby the pin and sleeve may move together to move the pinion into mesh with the engine gear and whereby the

55 sleeve may be rotated in case movement thereof is obstructed, said sleeve and pinion having clutching means for imparting rotation to the pinion; manually operable means for actuating said device; cooperating axially

60 65 engageable brake members connected respec-

tively with the shaft and with the sleeve, and a spring for returning the sleeve to normal or non-operating position and for causing the brake members to be engaged whereby motion of the shaft may be quickly arrested. 70

In testimony whereof we hereto affix our signatures.
